TWISTER SPINDLE

Theodore M. Cole, Waynesboro, Va., assignor to
 E. I. du Pont de Nemours & Company, Wil-
 mington, Del., a corporation of Delaware

Application July 3 1941, Serial No. 401,006

3 Claims. (Cl. 57—129)

This invention relates to method and means for reconditioning worn twister spindles of down-twisting machines.

Down-twisting machines such as ring twisters are commonly used for twisting textile yarns, and to increase productivity of the machine and to reduce operating costs the spindles supporting the bobbin on which the yarn is wound are rotated at high speeds and relatively large packages of twisted yarn produced. If the twister bobbin or pirn is carefully balanced and bushed precisely to just fit the spindle on which it is to be used so that there is substantially no freedom of motion between the bobbin and the spindle, the spindle can be used for a long period of time without excessive wear. However, in a textile plant equipped with tens of thousands of twister spindles and many more twister bobbins, it is impossible to keep all the spindles of the same uniform diameter, the bobbins statically and dynamically balanced and the bushings within the bobbins of sufficient precise bore to properly fit any spindle on which they may be put. As a result, the contacting surfaces within the twister bobbins become enlarged, eccentric holes and the spindle bearings become worn due to chatter and vibration and, as a consequence, those portions of the spindle engaging bearing areas of the bobbin are soon worn so badly that the spindle is no longer useful for its intended purpose.

Frequent rebushing of the twister bobbins or pirns helps but this is expensive. Twister bobbins more precisely made so that they will be better balanced statically and dynamically also materially helps in lengthening the useful life of the twister spindle. However, in spite of these and other improvements in this field, spindles generally become so badly worn within six months from their initial installation that they have had to be replaced by new spindles. This is, of course, costly in replacement materials, in labor and, most important, in loss of time and production of the twisting plant.

It is, therefore, an object of this invention to provide a simple and quick method for salvaging and reconditioning worn twister spindles whereby their life is prolonged several times over their initial useful period. A further object is in the provision of simple, economical means for reconditioning and prolonging the life of twister spindles on down-twister machines. Other objects of this invention will be apparent from the description that follows.

These objects are realized by my invention 55

which will be described in connection with the accompanying drawing wherein:

Fig. 1 is an elevation of a twister spindle and the supported bobbin, parts of which are cut away to show the areas of contact;

Fig. 2 is a view similar to Fig. 1 showing the twister spindle improved in accordance with a preferred form of my invention;

Fig. 3 is a cross-section, somewhat enlarged, on the line 3—3 of Fig. 2;

Fig. 4 is a detail sketch of a split sleeve; and

Fig. 5 is a detail of a portion of the spindle recessed according to my invention.

Referring to Fig. 1, 1 is the twister spindle 15 with its usual driving wafe 2 and driving key 3 coacting with a suitable slot in the bottom of the twister bobbin 4. The bobbin is centered on the spindle and held against wobbling by bearings 5, 6 near each end of the bobbin bore. It is at 20 these areas where the spindle contacts the bobbin that the customary steel spindles become badly worn due to the repeated hammering of the bobbin against the spindle as a result of vibration of the spindle, unbalance of the bobbin, etc.

The wear that takes place on the spindle at the areas of contact with the twister bobbin is very uneven and varies quite widely in depth. A typical spindle surface resulting from wear is shown (somewhat exaggerated) by the dotted 25 lines to either side of the bearings 5 and 6 in Fig. 1. To properly recondition a spindle that has worn to a surface depth of more than 0.007 or 0.008 inch, the worn area of the spindle is machined or ground to the necessary depth to 30 form a groove or recess 7 (Fig. 5) into which is fitted the contracting spring sleeve 8 shown in Fig. 4. It is necessary that there be a good tight fit between the inner surface of the split sleeve and the prepared section of the spindle 35 and that the outer surface of the sleeve when it is sprung in place on the prepared section of the spindle is uniformly flush all the way around with the rest of the spindle above and below this area, as shown in Fig. 2.

To further illustrate this invention, a worn spindle, the wear being entirely in the two areas previously mentioned, is machined and/or ground down to a uniform depth of 0.021 inch. In other words, if the original diameter of the 40 spindle or the diameter of the unworn portion of the spindle is, for example, 0.500 inch then the two prepared portions will each be 0.458 inch in diameter. The machining or grinding may be done with suitable jigs and fixtures so as to maintain concentricity of these prepared

areas. The split sleeves are prepared, for example, from spring steel stock 0.019 inch in thickness, then plated on the outside surface with chromium to the extent of 0.002 inch in thickness. In this way, the split sleeves having a total thickness of 0.021 inch just completely fill the spaces prepared for them on the spindle. The split sleeves are expanded over the spindle and slid in place and, due to the tendency of the material to contract and form a closed cylinder, 10 tightly hug the prepared areas of the spindle. If the preparation of the spindle and the manufacture of the split sleeves are carefully carried out, the sleeves will be held in place by frictional contact with the undercut portions of the spindle and the outer surface of the split sleeve will be just flush with the adjacent unworn portions of the spindle.

Spindles thus reconditioned have been found to resist wear exceptionally well and may be used several times the period that the spindles originally were in operation. Even after this extended period of continued use, a further reconditioning requires only replacement of the worn split sleeves with the new pair of split sleeves.

It is understood, of course, that the above description is by way of illustration only and that my invention is not limited to the exact material and conditions described, but is susceptible rather to wide variation. Thus, while a chromium plated split sleeve is preferred due to the desirable hard wearing surface of chromium, plain steel sleeves made of the proper thickness may also be used. The life of the plain steel sleeve will, of course, be considerably less as compared to the chromium plated sleeve, but the cost of their preparation is much less and in some instances, their use may be justified. Furthermore, instead of plating the steel sleeves with chromium, the plating metal may be of another material such as nickel. Instead of using spring steel sleeves any suitable hard wearing metal or metal alloy may be used providing it has sufficient springiness to clamp tightly around the cut-a-way portion of the spindle.

In some cases where the spindle wear is relatively small, for instance, where the maximum depth of wear is not over 0.008 inch and preferably not over 0.004 or 0.005 inch, that area may be carefully machined and ground and chromium plated directly therein and after finishing these prepared areas to make them smooth and flush with the rest of the spindle, an excellent wearing spindle is obtained. However, in general, this method is applicable only where the depth of wear is relatively small as indicated, for where the depth is substantial as,

for instance of the order of 0.020 inch, the amount of chromium plating becomes excessive and cannot be justified as a practical solution. Furthermore, when chromium is plated directly on the spindle rather than to the split sleeve, a subsequent reconditioning of the spindle cannot be so simply and easily carried out as is the case when my preferred method and means are employed.

By means of this invention, it has been found possible to recondition thousands of spindles which were heretofore thought worthless, but this invention does more than provide a method of reconditioning a spindle so that it is substantially as good as when it was new for spindles reconditioned in accordance with the preferred embodiment of this invention are vastly improved as compared with new unused spindles. Not only is the second useful period of their life several times the length of the first period, but because the period of wear is greatly increased, the quality of yarn prepared on twisting machines equipped with these spindles is improved. Furthermore, when it becomes necessary to replace a set of worn split sleeves, they can be quickly removed and a new set substituted in their place at very little effort and at low cost.

I claim:

- 30 1. In a down-twister machine for twisting and winding yarn, the improvement which comprises a bobbin supporting spindle said spindle being recessed throughout the area of its surface normally contacting the bobbin, the recessed area being covered by a sleeve of wear-resistant material.
- 35 2. In a down-twister machine for twisting and winding yarn, the improvement which comprises a bobbin supporting spindle said spindle being recessed throughout the area of its curved surface normally contacting the bobbin, and the recessed area being covered by a sleeve of wear-resistant material, said sleeve having a thickness equal to the depth of the recess.
- 40 3. In a down-twister machine for twisting and winding yarn, the improvement which comprises a bobbin supporting spindle recessed throughout the areas of its curved surface normally in contact with the bobbin, the recessed areas of said spindle being covered by split cylindrical sleeves of wear-resistant material which sleeves are of a thickness equal to the depth of the recesses, and which sleeves tend to contract whereby to form a close fit with the spindle and to form a substantially unbroken surface with the non-recessed surface of the spindle.

THEODORE M. COLE.
